Thos. J. Sprague

UNITED STATES PATENT OFFICE.

WRIGHT D. SMITH, OF DETROIT, MICHIGAN, ASSIGNOR TO THE HUYETT & SMITH MANUFACTURING COMPANY, OF SAME PLACE.

AIR-HEATING APPARATUS.

SPECIFICATION forming part of Letters Patent No. 374,094, dated November 29, 1887.

Application filed October 28, 1886. Serial No. 217,427. (No model.)

To all whom it may concern:

Be it known that I, WRIGHT D. SMITH, of Detroit, in the county of Wayne and State of Michigan, have invented new and useful Improvements in Air-Heating Apparatus; and I do hereby declare that the following is a full, clear, and exact description thereof, reference being had to the accompanying drawings, which form a part of this specification.

10 This invention relates to certain new and useful improvements in heaters for hot-blast apparatus or drying-machines.

The invention consists in the peculiar construction and combination of the parts with 15 relation to each other, as more fully herein-after described and claimed.

In the accompanying drawings, which form a part of this specification, Figure 1 represents my invention in perspective, with parts 20 of the wall of the air-heating chamber broken away to show the interior arrangement. Fig. 2 is a central vertical section of the fan-case and its flaring mouth.

A represents a box, preferably made of 25 sheet metal and rectangular in form, with an open discharge end communicating with the dry-kiln, which latter is not shown. The header-pipe B passes through the ends of this box, near one of its upper corners, and upon 30 its projecting ends, one being at either end of the box, a suitable cut-off valve, C C', is placed, and one of the projecting ends is connected with the exhaust of the engine that may be employed for driving the apparatus, 35 while the opposite end is connected with the live steam of the boiler, so that the exhaust or live steam may be used, as desired, by opening the proper valve for its admission and closing the opposite one.

40 D is a similar header-pipe extending along one of the lower corners of such box A, and projecting at both ends for the purposes of exhaust and live steam condensation and outlet, and these projecting ends are provided 45 with other suitable valves. Preferably this header-pipe D is diagonally opposite the header-pipe at the top of the box, and the two header-pipes are connected together by a series of steam coil-pipes, E, each coil being 50 independent from the others and connected

at top and bottom with the header-pipes B and D, care being taken that the area of both these header-pipes is not greater than the area of the pipes forming the coils in cross-section which enter them, thus allowing free 55 circulation without back-pressure on engine when the heater is being operated with exhaust-steam.

F is a ventilating-fan, which, when in motion, (driven from any suitable source of 60 power,) drives the air centrifugally into the box A, through the flaring mouth G, which affords communication between the fan and the interior of the box A, to which latter such flaring mouth is secured around an opening 65 large enough to admit of the centrifugal action of the air in being forced into the box, so that in the passage of such air through such box it is brought into contact with all, or nearly all, the radiating-surfaces of the pipes of the steam-coils and headers, and to this construction I attach importance.

I find by experience that with this construction I am able to heat a larger volume of air and to carry the same into the dry-kiln with 75 a great saving of labor to the fan, and that the air discharged into such dry-kiln is of a higher temperature when thus forced through the heating-chamber than when drawn through by a suction-fan located at the opposite end 80 of the heating-chamber to that where I locate my ventilating-fan, in which latter construction the fan agitates and cools the air.

For many commercial purposes hot air is 85 needed, and this device can be regarded as a hot-blast apparatus adapted to such purposes.

What I claim as my invention is—

The combination, in a hot-blast furnace, of the box A, inclosing steam-coils, with a disk-fan with its axis parallel with the length of 90 said box, and a flaring communication between the fan case and box, whereby the centrifugal force of the fan will drive the air into all parts of the box, substantially as and for the purpose specified.

W. D. SMITH.
